UNITED STATES PATENT OFFICE.

CHARLES L. STOKES, OF LOS ANGELES, CALIFORNIA.

LIQUID-FEED SYSTEM.

1,230,537.

Specification of Letters Patent. Patented June 19, 1917.

Application filed October 9, 1916. Serial No. 124,478.

To all whom it may concern:

Be it known that I, CHARLES L. STOKES, a citizen of the United States, residing at Los Angeles, in the county of Los Angeles, State of California, have invented new and useful Improvements in Liquid-Fee Systems, of which the following is a specification.

This invention relates to systems for feeding or lifting liquids, and, in its more particular phase, hereinafter described, relates to systems for feeding liquid fuel for internal combustion engines of any type.

It is an object of this invention to provide a simplified means for lifting liquid by the operation of suction; and particularly the operation of suction from an internal combustion engine to lift liquid fuel to a carbureter for the engine. It is an object of this invention to provide a form of means which may be readily combined with a carbureter; that is, which may be constructed as a unit with the carbureter, with the object of simplifying the combined construction.

In my co-pending applications S. Nos. 91,303 and 120,069, filed April 15, 1916, and Sept. 14th, 1916, respectively, I have explained and laid claims generally to mechanism for lifting liquid fuel from a low level tank to a high level service reservoir or tank to feed the carbureter, embodying admission of air to the liquid lifting line and the subsequent drawing of the admitted air into the engine intake. It is one of the objects of this present invention to make improvements upon said prior devices, particularly in the manner of admission of air to the fuel lifting line.

In such liquid feed systems as herein described, the liquid (the fuel) is lifted by suction to a reservoir, the suction being applied intermittently and atmospheric pressure being admitted to the surface of the liquid in the reservoir during the periods between the applications of suction so that the liquid in the reservoir may feed by gravity into the carbureter, the chamber of which is in communication with the atmosphere. It is an object of this invention to provide simplified means for cutting off the application of suction and for admitting atmospheric pressure to the liquid in the reservoir; and it is also an object, in connection therewith, to provide such means in such

form as to increase the lifting efficiency of the device.

The foregoing are among the objects of this invention; but others will appear from the following description of preferred forms of my invention and the illustrations thereof in the accompanying drawings, in which; Figure 1 is a diagram showing the various operative parts of my system and showing their relations and connections; Fig. 2 is an enlarged detail section of the connection to the main fuel tank; Fig. 3 is an enlarged detail section showing the means of admitting atmosphere to the service reservoir; Fig. 4 is an enlarged detail section of the service reservoir; Fig. 5 is a view similar to Fig. 1 showing another form of system in which the service reservoir and carbureter are combined as a unit; and Fig. 6 is an enlarged detail section showing the combined service reservoir and carbureter unit.

In the drawings the fuel tank is shown at 10 at a level lower than the carbureter 11 fed by the liquid from the tank. This tank has the usual filling plug at 12 with an air inlet to apply atmospheric pressure to the liquid in the tank. The lifting pipe 13 connects with the bottom of the tank as shown. The lifting pipe connects into a fitting 14 which has a liquid passage 15 communicating with the tank, and has also an air nozzle 16 controlled by a needle valve 17 to admit air into liquid flowing from the tank into pipe 13. The air is drawn through the pipe 18, whose upper end is above the liquid level in tank 10. The amount of air admitted at nozzle 16 may be regulated or completely shut off by valve 17. At a point intermediate in height between the tank 10 and the service reservoir 25, I connect an air pipe 26 with the pipe 13; the connection being through a very small drill hole 27, as shown in detail in Fig. 3. In practice, for the amount of fuel lifted for an ordinary automobile, this drill hole 27 is of about the size of a No. 60 drill. The stand pipe 26 is solely for the purpose of preventing the escape of fuel in the event of going down a steep grade or in other conditions where the hole 27 may be lowered below the level of the fuel in the tank 10.

The pipe 13 leads to the top of the service reservoir 25 and discharges into that reservoir through the cover 30 and through a

nipple or baffle 31 extending into the reservoir beneath the cover; this baffle being for the purpose of preventing the mixed air and liquid being drawn immediately to the suction port 32 before the air and liquid can separate. The suction pipe 33 extends from the intake manifold 34 of the engine (at a point above the throttle valve 35) to the suction port 32 of service reservoir 25. 5 A valve 36 is adapted to close the port 32 by upward movement; and this valve is mounted upon a lever 37 pivoted at 38 and engaging at its free end with sleeve 39 of float 40; the engagement being such that the lever moves up and down with the float. 10 This float is preferably somewhat weighted (as compared with the weight of ordinary floats of this character) so that its weight is sufficient to pull the valve 36 down against the suction tending to keep it up, when the liquid level in reservoir 25 has fallen so that the liquid support of the float is partially withdrawn. From the lower part of reservoir 25 the liquid fuel passes out through 15 pipe 40 to the carbureter 11, passing the upwardly closing valve 41, provided for the purpose of keeping the fuel in the carbureter from being sucked back into the reservoir 25 when suction is applied to the reservoir. 20 The valve 41 may be placed at the carbureter and seated by gravity, as shown in Fig. 6.

I now explain the action of the system, said action being the same for both forms of system illustrated, with the exceptions hereinafter noted.

When the service reservoir is full of liquid the float 40 moves up to the position shown and moves the valve 36 to close suction port 32. The closure of this suction port prevents further application of suction to the reservoir. Gradual flow of liquid out of the reservoir to the carbureter lowers the liquid level in the reservoir and takes away the liquid support of float 40. When the liquid level has fallen to such an extent that the unsupported weight of the float is sufficient to overcome the suction tending to support valve 36, then the float will fall, carrying valve 36 with it and suction will be reapplied to the upper part of the reservoir. In an actual apparatus the arrangement is made such that the liquid level in the reservoir only falls through a small distance before the valve 36 is moved downwardly. 65

Suction being applied to the reservoir, is of course, also applied to pipe 13. The liquid from tank 10 normally stands up in pipe 13 to a height depending upon the amount 60 of liquid in the tank; but the air port 27 is always higher than the normal liquid level. Suction applied to pipe 13 will immediately begin to draw air into the port 27; but the amount of air introduced 65 through this port is insufficient to break the

suction. The fuel therefore begins to rise in pipe 13 and, after passing port 27, this fuel is intermingled with the air drawn through the port. The valve 17, at the lower end of pipe 13, may be regulated to 70 also admit a restricted quantity of air, or this lower admission of air may be entirely done away with; so that the fluid rising to port 27 may either be mixed liquid and gas or pure liquid. In any case, a certain 75 amount of air is introduced at the port 27, and the column of mixed liquid and air is then drawn up through the pipe 13 and over into the reservoir 25, where the liquid and air separate, the air being drawn into the engine manifold and the liquid settling into the body of liquid in the reservoir. As the liquid level in the reservoir rises, the float 40 is moved upwardly until the valve 36 is again seated, cutting off the application of 80 suction. Immediately the application of suction is cut off, the column of mixed liquid and air in pipe 13 is arrested in motion and the liquid settles back through the pipe to its normal level. By this action the port 27 is again uncovered and communication with atmosphere is restored to the reservoir 25 through the pipes 13 and 26. 85

It will now be seen that the air port 27, located at a point above the normal level of 90 liquid, performs two functions; one to admit atmospheric pressure to the liquid in the service reservoir when suction is not being applied and when the atmospheric pressure is needed to allow the liquid in the service reservoir to flow out; and the other being to supply air to the rising column of liquid in pipe 13 to facilitate the upward movement of the column. So far as either function of port 27 is concerned, it is more or less immaterial whether air is admitted at the lower end of pipe 13; although the admission of some air at the lower end of the pipe facilitates somewhat the raising of the mixed column of air and liquid. The point at which port 27 enters the communication depends more or less on the vertical distance through which the liquid is lifted. If the lift is short the port may be very close to the service reservoir; in fact it may 100 be at the service reservoir itself. 105

With the arrangement as described, it will be seen that the service reservoir is always open—restrictedly open—to atmosphere at all times. The atmospheric port 110 need not at any time be closed. This is a distinctive feature of my device; and a distinctive feature of operation arises therefrom—that the fuel fluctuating in the lifting line alternately covers and uncovers 115 the atmosphere port, and that atmosphere is constantly passing into the reservoir either to be drawn into the engine or to replace the volume of fuel going to the carbureter. 120

The operation of the system shown in Figs. 5 and 6 is essentially the same as that just described. In these figures I show the service reservoir 25^a constructed in a unit 5 with the carbureter 11^a. The service reservoir has the same float 40 operating the valve 36 through the medium of the lever 37 connected at 39 with the float. The suction pipe 33 connects in the same manner as before described with the intake manifold 34 of the engine above the throttle valve 35. The carbureter itself may be of any of the usual constructions; embodying, for instance, the liquid nozzle 50 controlled by needle valve 51 and located in the air passage 52 which connects directly with the intake manifold of the engine. Liquid fuel is supplied to the nozzle 50 from the fuel chamber 53, which is in communication at 54 with atmosphere. 10 But this chamber has no float or valve as is ordinarily the case. A horizontal liquid passage 55 may connect the bottom of reservoir 25^a with the bottom of chamber 53; and any suitable check valve, indicated at 56, may be placed in this communication to prevent back flow of liquid from chamber 53 to reservoir 25^a when suction is applied to the reservoir. Whenever the liquid level in reservoir 25^a is higher than that in chamber 53, 15 liquid will flow from the reservoir to the chamber to replenish the supply in the chamber. The maximum height of liquid in chamber 53 is level with the maximum height in reservoir 25^a; and this maximum height is controlled entirely by the action of float 40 and valve 36; because whenever the valve 36 is closed, it is impossible to introduce liquid into the reservoir by the suction action. 20 In this last explained form of system, it will be seen that the float 40 not only acts to maintain the level of liquid in the chamber 25^a but also acts to maintain the level of liquid in chamber 53 and to limit the rise of liquid in that chamber. Consequently, the float 40 performs a double function in that it controls the application of suction to the service reservoir and controls the lifting of liquid from tank 10 and the filling of the 25 reservoir, and also controls the liquid level in the chamber 53 which directly and immediately feeds the carbureter proper, particularly in case where the level of the carbureter may be below that of the fuel in tank 10. 30 Having described a preferred form of my invention, I claim:

1. In a liquid feed system for an internal combustion engine, the combination of a liquid tank, a liquid reservoir above said tank, communication between the tank and the reservoir, means for admitting atmosphere to said communication above the normal liquid level therein and below the normal liquid level in the reservoir, means for 35 applying suction to the upper part of the

reservoir said means carrying the admitted atmosphere to mix with the carbureted charge of the engine, and float-actuated valve means for cutting off suction to the reservoir.

2. In combination, a carbureter having a liquid fuel chamber open to atmosphere, a liquid fuel reservoir in communication with said chamber, means to prevent passage of the liquid fuel from the chamber to the reservoir, and float controlled suction means for introducing liquid fuel to the reservoir, said means including, in combination with a liquid fuel tank at a level below the reservoir, a communication pipe leading from the fuel tank to the upper part of the reservoir, means to restrictedly introduce atmosphere to the communication pipe at a point to enter the column of liquid moving upwardly therein, means to apply suction to the upper part of the reservoir, a float and a valve operated by the float to cut off suction from the reservoir when the liquid level in the reservoir reaches a predetermined point.

3. In combination with a carbureter having a fuel chamber open to atmosphere, a low level liquid fuel tank and a high level service reservoir feeding the carbureter chamber by gravity, communication between the tank and reservoir, means to intermittently apply suction to the reservoir, and means to restrictedly admit atmosphere to said communication at a point above the normal level of liquid therein and at a point to enter the column of liquid moving upwardly therethrough.

4. In combination with a carbureter having a fuel chamber open to atmosphere, a low level liquid fuel tank and a high level service reservoir feeding the carbureter chamber by gravity, communication between the tank and reservoir, means to controllably apply suction to the reservoir, and means to restrictedly admit atmosphere to said communication at a point above the normal level of liquid therein and at a point to enter the column of liquid moving upwardly therethrough.

5. In combination with a carbureter, a low level liquid fuel tank, a liquid fuel reservoir above the carbureter and in communication with it to supply it with fuel, communication between the tank and the reservoir, means for restrictedly admitting atmosphere to said communication above the normal liquid level therein and at a point where the admitted atmosphere enters the upwardly moving column of liquid moving from the tank to the reservoir, and communication means to intermittently apply to the upper part of the reservoir the same suction that is applied to the carbureter to maintain a partial vacuum in the reservoir and to draw therefrom the air which enters it with the fuel.

6. In combination with a carbureter, a low level liquid fuel tank, a liquid fuel reservoir above the carbureter and in communication with it to supply it with fuel, communication between the tank and the reservoir, means for restrictedly admitting atmosphere to said communication above the normal liquid level therein and at a point where the admitted atmosphere enters the upwardly moving column of liquid moving from the tank to the reservoir, communication means to apply to the upper part of the reservoir the same suction that is applied to the carbureter to maintain a partial vacuum in the reservoir and to draw therefrom the air which enters it with the fuel, and means depending upon the level of liquid in the reservoir to discontinue the application of suction to the reservoir.
7. In combination with a carbureter having a liquid fuel chamber open to atmosphere, a low level liquid fuel tank and a high level service reservoir feeding the carbureter chamber by gravity, communication between the tank and reservoir, means to restrictedly admit atmosphere to said communication at a point above the normal liquid level therein and below the normal liquid level in the reservoir, and means to intermittently apply to the upper part of the reservoir the same suction that is applied to the carbureter to maintain a partial vacuum in the reservoir to draw therefrom the air which enters the reservoir with the liquid fuel.
8. In combination with a carbureter having a liquid fuel chamber open to atmosphere, a low level liquid fuel tank and a high level service reservoir feeding the carbureter chamber by gravity, communication between the tank and reservoir, means to restrictedly admit atmosphere to said communication at a point above the normal liquid level in the reservoir, means to apply to the upper part of the reservoir the same suction that is applied to the carbureter to maintain a partial vacuum in the reservoir and to draw therefrom the air which enters it with the fuel, and valve means controlled by the level of liquid in the reservoir to discontinue the application of suction thereto.
9. In combination with a carbureter having a liquid fuel chamber open to atmosphere, a low level liquid fuel tank and a high level service reservoir feeding the carbureter chamber by gravity, communication between the tank and reservoir, means to restrictedly admit atmosphere to said communication at a point above the normal liquid level therein and below the normal liquid level in the reservoir, means to apply suction to the upper part of the reservoir, and valve means controlling the application of such suction embodying a valve and float means to close the valve when the liquid reaches a predetermined high level and to open the valve when the liquid reaches a predetermined low level, said levels being separated by a predetermined distance.
10. In a liquid feed system for an internal combustion engine, the combination of a liquid tank, a liquid reservoir above said tank, communication between the tank and the reservoir, means for admitting atmosphere to said communication above the normal liquid level therein and below the normal liquid level in the reservoir, said means including an air supply passage extending upward and communicating with the atmosphere at a point above the maximum level of the liquid in said reservoir, means for applying suction to the upper part of the reservoir, said means carrying the admitted atmosphere to mix with the carbureted charge of the engine, and float-actuated valve means for cutting off suction to the reservoir.
- In witness that I claim the foregoing I have hereunto subscribed my name this 30th day of September, 1916.
- CHARLES L. STOKES.
